UNITED STATES PATENT OFFICE.

HERBERT H. CHRISMAN, OF MINNEAPOLIS, MINNESOTA.

COMBINATION-LOCK.

1,235,515.

Specification of Letters Patent. Patented July 31, 1917

Application filed August 4, 1915. Serial No. 43,600.

To all whom it may concern:

Be it known that I, HERBERT H. CHRISMAN, citizen of the United States, resident of Minneapolis, county of Hennepin, State 5 of Minnesota, have invented certain new and useful Improvements in Combination-Locks, of which the following is a specification.

The object of my invention is to provide a 10 device in connection with the battery or magneto circuit of an automobile to prevent any unauthorized person from starting the car and to dispense entirely with locks and keys.

15 A further object is to provide a device having keys for controlling the different lights of the car.

Other objects of the invention will appear from the following detailed description.

20 The invention consists generally in various constructions and combinations, all as hereinafter described and particularly pointed out in the claims.

In the accompanying drawings forming 25 part of this specification,

Figure 1 is a plan view of the lock device with the cover raised,

Fig. 2 is a vertical sectional view on the line $x-x$ of Fig. 1,

30 Fig. 3 is a sectional view on the line $y-y$ of Fig. 1,

Fig. 4 is a sectional view on the line $z-z$ of Fig. 1.

In the drawing, 2 represents a suitable 35 box or casing, in which the lock is mounted. Within this box I arrange a series of plates of conducting material, preferably copper, designated by reference numerals 2', 3, 4, 5, 6, 7, 8 and 9, alternating with a correspond- 40 ing number of insulating plates 10, which separate the conductor plates from contact with one another. The conductor plates and the insulating plates have tapered sockets 11 therein and pins 12, 13 and 14, of suitable 45 conducting material, such as copper, are mounted to slide in said sockets and have collars 15 and 16 formed thereon in such a position that they will bear on the walls of the sockets in the conductor plates and 50 make a rubbing contact therewith. These conductor plates form terminals for the line circuits and the plates 2', 5, 7 and 9" have binding posts 17, 18, 19 and 20 at one end, and the plates 6, 8, 9 and 9' have similar 55 posts 21, 22, 23 and 24 at the opposite ends

of the plates. The collars 15 and 16 on the pins 12, 13 and 14 are spaced apart and are preferably tapered to conform to the taper of the pins, and when the pins are forced into the sockets, the collars will close the 60 circuit through the pins between the conducting plates. Said pins preferably have heads 25 and springs 26 are mounted to engage said heads and hold them either in their depressed or raised position. 65

In Fig. 2 the circuit is shown as closed between the terminal 17, the plates 2' and 3, thence through the collars on the pin 13 and plates 3 and 4 and the collars on the pin 14 to the terminal 18, and from thence 70 through the conductor 27 to the engine (not shown) and back through the battery B and conductors 28 to the terminal 17 of the plate 2', thus completing the battery or magneto circuit and producing a spark to start 75 the engine. 30 is a cover, hinged at 31 to the casing and in this cover a series of keys 32 are mounted and normally held in a raised or projected position by springs 33. These keys are all alike and in this lock I 80 have shown a group or bank of 16 of them, but this number may be increased or diminished, as desired.

The keys are in alinement with the pins, and when the proper keys are depressed, the 85 pins controlling the electric circuit will be operated to close the circuit through the battery and the magneto. Beneath some of the keys I provide a group of dummy pins, one of which I illustrate in Fig. 2 and 90 designate by reference numeral 34. This pin has collars 35 and 36 thereon to make contact with the plates 2' and 7 which are in circuit with the battery through the terminals 17 and 19 and with an electro-magnet 37. The armature 38 of this magnet is pivoted at 39 and connected on the opposite side of its pivot with a rod 40 which extends down through the insulating and conducting plates, and is connected to a plate 41 100 which is yieldingly held in a depressed position by a spring 42. When the circuit is closed through the magnet 37, this plate 41 will be quickly raised and should the person seeking to work the combination have 105 depressed any one of the right pins, 12, 13 or 14, and should close the circuit through the magnet by the depression of one of the other pins, the quick upward movement of the plate 41 will immediately lift the proper 110

pin, which may have been depressed, and thereby positively prevent the solution of the combination. There being in this particular lock some twelve interchangeable 5 keys, and only three of them belonging to the combination, it is quite evident that a person entirely ignorant of the combination would hardly be able to select the three right keys in succession, but in case he should 10 pick out two of them correctly and then strike the wrong key and depress one of the pins 34, the plate 41 would immediately be thrown upward and the pins that he may have correctly operated will be thrown back 15 to their normal position. It will thus be extremely difficult for any one not understanding the combination to pick out the proper keys. Furthermore, whenever desired, the arrangement of the keys in the 20 lock may be changed, assuming that some one has detached the combination or learned the order of the keys and their relative arrangement. By shifting them about confusion will be sure to result and unless a 25 person is familiar with the location of the proper pins it will be practically impossible for him to work the combination.

For the purpose of locking the cover 30 but permitting access to the pins to shift 30 them about in the plates, I prefer to provide an electro-magnet 43 in circuit with the terminals 17 and 21. The armature 44 of the magnet 43 has a dog 45 which engages a flange 46 of the cover and normally locks 35 it in place. When the key 46' controlling the cover locking pin is depressed (see Fig. 3), the circuit will be closed through this pin and the plates 2', 3, 4 and 6, providing the pins 12, 13 and 14 are in place, and 40 through the magnet 43 energizing the armature to release the cover and allow it to be raised to permit access to the pins. I will trace the circuit between the terminal 17 and the magnet 43 as follows: through conductor 45 28 and battery B to terminal 17; through plate 2' and pin 12 to plate 3, pin 13 to plate 4 and from plate 4, assuming that the pin 46' has been depressed to plate 6, thence to terminal 21 and back to the magnet 43. 50 I also prefer to provide a group of pins 47, 48, 49 and 50 controlling respectively the tail and head lights, the body light and the door, each pin being actuated by a key corresponding to those described with reference 55 to Fig. 2 and mounted in the cover in position, when depressed, to actuate the pin beneath and close the respective circuits therefor. As here shown, conductors 51, 52 and 52' are connected to the plates 9, 9' and 60 9'', and the body light is on through a depression of the pin 49 and the closing of the circuit through the plates 2' and 9''. The pins have the other circuits here illustrated in their raised position where, however, they

will be forced down by the depression of the 65 keys.

I claim as my invention:

1. A combination lock comprising a series of substantially flat conductor plates arranged in parallel relation and insulated 70 from one another, said plates having a series of sockets extending therethrough and through the insulation between them, a series of selective circuit closing pins fitting within said sockets, and an electric circuit 75 closed by the movement of a predetermined combination of said pins.

2. A combination lock comprising a series of insulated conductor plates having sockets therein, circuit closing pins fitting within 80 said sockets, an electric circuit closed by the movement of a group of said pins, and means for returning all the pins to their normal position in case the operator should move a pin not in said group. 85

3. A combination lock comprising a plurality of insulated plates having sockets therein, circuit closing pins fitting within said sockets, an electric circuit for certain 90 of said plates, a second electric circuit for others of said plates, a series of corresponding actuating keys, some of said keys operating said circuit closing pins to close said first named circuit, mechanism actuated by other keys for closing said second named 95 circuit, and means operative by the closing of said second named circuit for returning said circuit closing keys to their normal position.

4. A combination lock comprising a series 100 of insulated plates having sockets therein and pins for said sockets, some of said pins having means for closing the circuit through certain of said plates and other pins having means for closing the circuit through other plates, terminals and conductors for said plates, actuating keys for said pins, an electric circuit closed by the movement of some of said pins and having means for returning said circuit closing pins to their normal 110 position.

5. A combination lock comprising a series 115 of circuit-closing pins, an electric circuit closed by the movement of a certain combination of said pins and electrically actuated means made operable by the movement of a pin not in the combination for rendering the movement of the pins in the combination ineffective.

6. A combination lock comprising a series 120 of insulated conductor plates having sockets therein, circuit closing pins fitting within said sockets and an electric circuit closed by the movement of a predetermined combination of said pins and a group of keys 125 for actuating said pins.

7. A combination lock comprising a series of insulated plates having sockets therein

and pins for said sockets, the combination of certain of said pins closing the circuit through some of said plates and other pins closing the circuit through other plates, an electric circuit closed by the movement of some of said pins and having an electro-magnet and armature therein, and a striker plate connected with said armature and actuated thereby to return said combination pins to their normal positions in case of failure to operate them successively or by operating more pins than are in the combination.

8. A combination lock comprising a suitable casing and a cover therefor and a locking device for said cover, an electro-magnet for controlling said locking device, terminals in circuit with said electro-magnet and having contact plates, a pin for closing the circuit through said plates and magnet, and other circuit closing pins arranged in combination for completing the circuit between said first named pin and magnet.

9. A combination lock comprising a series of circuit pins, an electric circuit closed by the movement of a certain combination of said pins, and electrically actuated means for automatically returning all of said pins

to their normal position when a pin not in the combination is operated.

10. A combination lock comprising a series of insulated plates having sockets therein, an electric circuit having terminals on some of said plates, pins fitting said sockets for closing the circuit between said plates, some of the pins closing the circuit through certain of said plates and other pins closing the circuit through other of said plates.

11. A combination lock comprising a series of conducting members arranged in substantially parallel relation and insulated from each other, an electric circuit having terminals on said members, said members having sockets therein, those of one member being arranged to register with the corresponding sockets of the other members, circuit closers fitting said sockets for contacting with said members to close the circuit between them, some of said circuit closers closing the circuit through certain of said members and other circuit closers closing the circuit through other of said members.

In witness whereof, I have hereunto set my hand this 28th day of July 1915.

HERBERT H. CHRISMAN.
